(57) **CLAIM**

The ornamental design for a swivel chair, as shown and described.

DESCRIPTION

FIG. 1 is a perspective view of a swivel chair showing my new design;

FIG. 2 is a front view of the design;

FIG. 3 is a rear view of the design;

FIG. 4 is a left-side view of the design;

FIG. 5 is a right-side view of the design;

FIG. 6 is a top plan view of the design; and,

FIG. 7 is a bottom plan view of the design.

The broken lines shown in the drawings are for illustrative purposes only and form no part of the claimed design.

The claimed design is implemented on any article of metal material and synthetic resin.

The claimed design is composed of various materials such as mesh in back of a chair for domestic and office. The claimed design is a different from any former designs, which has prior shape and thus, it has a new sense of beauty and simple figure.
